UNITED STATES PATENT OFFICE.

WALTER J. SPENCER, OF BINGHAMTON, NEW YORK.

COOLER FOR FROSTING.

Application filed January 12, 1927. Serial No. 160,582.

My invention relates to coolers for cakes and food stuffs and the frosting placed thereon.

One object of my invention is to provide a mechanical means for the rapid cooling of cakes and the frosting placed thereon.

Another object is to provide means for automatically producing these results simultaneously upon varied forms of food products and at the same time providing for the process, a continued action, and also providing a protection from dust and other foreign matter in the air.

With these objects in view my invention consists of the following novel features of construction and arrangement of parts as will be hereinafter fully described and pointed out in the claims, reference being had to the accompanying drawings in which:—

20 Fig. 1, is a perspective side view of the exterior of my device.

Fig. 2, is a side interior view in cross section of my device.

25 Fig. 3 is an end view in cross section of my device.

Fig. 4 is a side interior view in cross section of a fragmentary part of my device.

Fig. 5, is a plan view of a part of my device.

30 Fig. 6, is a perspective end view of my device.

The same reference characters denote like parts in each of the several figures of the drawings.

35 In carrying out my invention I provide a rectangular housing A, having double parallel sides, top and end walls a, a, spaced apart and forming an outer and inner wall, the housing having an open bottom. The top of the housing may be in a curved outline as shown in Figs. 1 and 6. Within the housing

40 I have constructed three vertical parallel partitions 5, 6, and 6'; these partitions extend downward from the interior surface of the inner top wall of the housing to a point near the lower edge of the side and end walls of the housing A. These partition walls are composed of the central wall 5 and the two end walls 6 and 6', dividing the housing into

45 4 chambers, designated as A¹, A², A³, A⁴. In the upper portion of each end partition wall 6 and 6' I have a circular opening 7 and mounted in any convenient manner in each opening 7 I have the electrically operated

50 fan 8 having a motor 9 connected therewith,

mounted on standard 10. From the lower end of each partition wall 6 and 6' I have a floor 11 extending longitudinally from the lower edge of the partition wall towards the central partition 5; this floor also extends 60 across between the interior side walls of the housing. An open space 12 extends between the end of floor 11 and central partition wall 5. Mounted horizontally between the end partition walls a and the interior end 65 wall surface of the housing A, and between the partition wall 6' and the interior of the end wall surface of the housing A, I have a series of blind slats 13, 13, 13, pivotally mounted between the interior walls of the 70 housing A and in the walls of the same, the lower edges of which slats are on a line with the floor 11 and I have an operating rod 14 linked in the usual manner with the upper edges of the blind slats 13, 13, as shown in 75 Figs. 2 and 3 and 4. Mounted on the outer end of one of each of these series of blind slats and extending thru the side walls of the housing A, I have the crank handle 15, for operating the blind slats for opening and 80 closing; the lower edges of the side and end walls of the housing A are removably mounted on the table or other supports B in any convenient manner; also removably mounted on the supporting table B, I have an elongated frame structure C, having the side and cross bars 16 and 17, and the legs 18, the size and form of the frame structure C is such that the housing A may be placed down over the frame C, the legs 18 raise the frame 85 structure, so as to leave the open under space or passage way 19 between the bar 17 and legs 18, and the top of the table surface B; mounted in any convenient manner on the frame C I have a series of metal pipes or 90 tube structures D; this series of tube structures D consists of the parallel connecting tubes or pipes 20, 20, 20, and 20', 20', 20', in horizontal alinement, one or more layers, one over the other, such as b and c; mounted 95 upon the tubing I have the connecting valve 21; these tubes are for the purpose of containing suitable air cooling refrigerating elements; along rack C in housing A, mounted in any convenient manner around the outer 100 sides and ends of the tube layers b and c, I have a narrow sloping side or wall strip E, the upper edges of which are adjacent to the interior surface of the inner wall of housing A, and the lower edge adjacent to the upper 110

layer of piping C; an open space 22 is left in each end wall of housing A below the lower line of rack bar 17' and above the surface of the table support B which permits of a passage way thru the housing A and under rack C and over the supporting surface B; on the surface B and thru the passage way 22 I have arranged an endless belt F which in movement rests upon the surface B and which may be operated in any convenient manner.

In the operation of my device having the table or platform B and the operative endless belt F in position as before mentioned, I arrange the electrical power connection for the movement of the belt F; on the table support B I mount the rack C, and on the rack C is mounted the piping D; having thus mounted the rack and piping, I surround the piping with the sloping strap or guard E for the purpose of more completely concentrating the air current against the tubes; I then place over the rack and piping the housing A, having in it the fans 8, 8 before mentioned and the electric motors 9, 9; the valve 21 controls the flow of refrigerating material; when the piping has reached the proper refrigerating temperature I supply the electrical power to the fans 8, 8 and the movement of the fans causes a circulation of the air over the piping D, and through the opening 12 and into chambers A, A¹ and A⁴, as shown by the line of arrows in the Figs. 1 and 4, and again over the piping and down into the passage way 22 and on to the food stuffs and frosting 23, 23; the food stuffs are placed upon the belt F outside the housing, and are passed through the housing on the belt F and thus they come in contact with the circulation of the cold air as they are moving through the passage way 22, and the air in its passing is directed against the chilled tubing by means of the guard E around the piping D; I can control at all times the air current by the opening and

closing of the slats 13, 13 by means of the handle 15.

Having thus described my invention what I claim as new and for which I desire Letters Patent is as follows:

1. In a cooler for frosting, a portable housing having double walls and top, spaced apart, and open bottom, the interior of the housing divided by vertical partitions into a plurality of chambers, openings in the partitions in which operated fans are positioned, means for operating the same, pivotal blind slats mounted in the floor line of the chambers for controlling the outlet of air and the open space in the floor line of the adjacent chamber for the inlet of air, a platform supporting the housing and having thereon mechanical means for cooling the air after passing into the housing chamber and in passing out of the housing chamber, and means for automatically conveying food stuffs through the housing and in contact with the cooling air passing out of the housing chamber.

2. In a cooler for frosting, a rectangular housing removably mounted on a platform and having a vertical opening in the lower edge of each end, vertical partitions dividing the interior into a plurality of chambers, an opening in one or more of the partitions, a fan mounted opposite each opening and means for operating the fans, each opposite end chamber of the housing having a raised flooring of blind slats, means for operating the same, two opposite intermediate chambers having each a raised flooring with an opening therein, a support removably mounted on the platform and beneath the flooring, refrigerating coils mounted on the support, and a belt conveyer passing through the housing.

In testimony whereof I have affixed my signature.

WALTER J. SPENCER.
